UNITED STATES PATENT OFFICE.

STILLMAN W. ROBINSON, OF COLUMBUS, ASSIGNOR TO THE ROTE AUTOMATIC BRAKE COMPANY, OF MANSFIELD, OHIO.

AUTOMATIC CAR-BRAKE.

SPECIFICATION forming part of Letters Patent No. 317,859, dated May 12, 1885.

Application filed February 2, 1885. (No model.)

To all whom it may concern:

Be it known that I, STILLMAN W. ROBINSON, of Columbus, county of Franklin, and State of Ohio, have invented a new and useful Improvement in Automatic Car-Brakes, of which the following is a full, clear, and exact description, reference being had to the accompanying drawings, making part of this specification.

10 My invention relates to certain details of improvement in the car-brake mechanism upon which Letters Patent were granted to C. V. Rote, March 20, 1883, No. 274,389; and it consists in a novel construction of the curved levers through which the weighted axle-levers or governor-arms act on the gravity-stop for relieving the brake-setting mechanism, whereby the release of said axle-levers from and their engagement with the curved levers is 20 facilitated; in a novel construction of the weighted axle-levers or governor-arms operating in connection with the curved levers; in a novel arrangement of gravity-stop, in connection with the cam-lever, for setting or releasing the brake-setting mechanism, and with the curved levers for releasing said gravity-stop, and in certain minor details of construction and arrangement of parts hereinafter fully described.

30 In the accompanying drawings, Figure 1 represents a plan view of a portion of a car-platform frame and truck, with parts broken away to show the brake-setting mechanism underneath. Fig. 2 represents a vertical longitudinal section through the same, showing the brake-setting mechanism in side elevation. Fig. 3 is an end view of the bracket or hanger supporting the cam and brake levers. Fig. 4 represents a vertical section through the 40 axle, showing the curved levers and weighted axle-levers or governor-arms enlarged, as compared with Fig. 2; and Fig. 5 is a plan view of the parts shown in 4, with the curved levers in section.

45 A indicates the platform-frame of the car, which may be of any usual or preferred construction, and A A² parallel longitudinal timbers thereof, located near the center of the width of the car—one on each side thereof—and between which, or between pendent guides or hounds secured thereto, is located the sliding draw-head C, provided with the usual buf-

fer-spring, and carrying on its lower face a pivoted block or dog, D. To the timber A² is secured a pendent angular bracket, a, in the horizontal portion of which the brake-lever E and the cam lever F are pivoted in the same horizontal plane with the dog D, and adapted to operate in connection therewith in a manner similar to the operation of the corresponding parts of the Rote brake, referred to, the brake-lever E being connected with and serving to operate the brakes in a similar manner.

B represents a portion of the truck-frame, and B' one of the axles thereof, and to any suitable part of the truck-frame which maintains a fixed relation to said axle is secured an angular bracket, in the outer or free end of which, overhanging said axle, the curved pendent levers K K' are pivoted, with the pendent curved arms thereof embracing the axle between them, as shown. These levers in practice are operated upon by the weighted levers or governor-arms on the axle in a manner similar to that described in the Rote patent, referred to, and may be connected through an intermediate lever or levers with the gravity stop or pin for locking and releasing the cam-lever in a similar manner; but I prefer the construction of said levers and the arrangement of gravity-stop which I will now describe. Instead of making the pendent arms of the levers K and K' semicircular in form, I make them approximately crescent-shaped, whereby they are made to diverge from the axle toward their points or lower ends, and also in the parts adjacent to the pivot i, this construction giving them the relieving-points necessary to enable them to engage as well as to release the governor-arms without cutting away the levers at such points, as in the patent referred to, thereby simplifying and reducing the cost of their construction.

The weighted levers or governor-arms P are pivoted in suitable lugs or ears, n, in the divided sleeve N, which is clamped to the axle. They are made in elbow or bell-crank form, and are pivoted at the elbow in the lugs n, as shown. The weighted arm P, when the car is in motion, will be thrown outward away from the axle, causing the other arm, p', to hug or rest upon the axle or sleeve N, and the arm p' is expanded in width, and by preference has its end made slightly concave, as

shown at p^2 , so that when the weighted arms fall inward upon the axle, in consequence of a reduction in the speed of rotation of the latter, said curved end will engage and crowd 5 outward away from the axle the curved arms of the pendent levers K and K', the concave ends p^2 serving to prevent lateral displacement of the levers when engaged by said governor-arms. The weighted arms of the governor are thus made each in a single piece, and are thereby simplified and made more positive and certain in action than when they are made up each of several parts, one part depending for its action upon another.

15 The curved levers K and K', instead of having horizontal arms or heel-extensions beyond their pivots for connecting with the gravity-stop levers, as in the Rote patent, and as indicated in dotted lines in Fig. 4, are made—20 one of them, K'—to terminate at the pivotal point, while the other is provided with an upright arm, k, extended above the pivot, and connected by a rod, g, with a pendent latch lever or stop, I, pivoted to the frame-timber 25 A² or other suitable support, (see Fig. 2,) the pendent curved lever K' being also connected with said latch-lever I by a rod, g'. By this arrangement, when either of the curved levers K or K' is vibrated outward or away from 30 the axle by the action of the weighted axle-levers or governor-arms, the latch-lever I will also be vibrated away from the axle and from its vertical position.

The cam-lever F, when in position to cause 35 the pivoted dog D to act on the brake-lever E, extends obliquely across the plane of and below the timbers A' A², and its extreme end is caught and held by the pendent latch-lever I whenever the car is being drawn at speed 40 sufficient to free the pendent curved levers K and K' from the action of the governor-arms; but when the speed of the axle is so reduced as to cause the governor-arms to act upon said 45 curved levers K and K', or either of them, and thus to crowd them outward, as explained, the latch-lever I will also be thrust outward sufficiently to release the end of the cam-lever F, and thereby allow the pivoted dog to pass by the end of the brake-lever without acting 50 upon it to apply the brakes. The latch-lever I is suspended in such manner and its connection with the levers K and K' are such as to adapt it by gravity of the parts to swing down into position to engage and hold the cam-lever F when the car is being drawn forward 55 at all times when said latch is not held up or away from said lever by the action of the weighted axle-levers. When the car is being backed, the cam-lever will be thrown out of 60 the position to be caught by the gravity stop or latch.

A light spring, l, attached at one end to the bracket a and at its other end to the lever F, serves to hold the latter normally in position 65 to be engaged by the latch-lever I, but is not of sufficient strength to interfere with the free vibration of said cam-lever when not held

by the latch-lever under the action of the dog D; and to assist the spring l in returning the cam-lever to proper position to be engaged by the latch-lever after the cam-lever has been vibrated away from such position by the action of the dog D, said cam-lever has formed upon or secured to it a curved heel-extension, f, extending outward and around 70 within the path of the dog D, when the latter is drawn outward with the draw-bar C, in such manner that the dog acting on said heel extension or arm f serves to retract the cam-lever and to bring it into position to be caught 75 by the latch-lever.

Having now described my invention, I claim as new—

1. The combination, with the weighted levers or governor-arms controlling the brake-actuating mechanism, of the curved levers partially surrounding the axle and made substantially in crescent form, whereby they are adapted to be engaged by and to release the governor-arms without the aid of relieving 90 points or notches in the levers, substantially as described.

2. The combination, with the pendent curved levers embracing the axle between them, of the weighted axle-levers made each in a single piece and arranged to operate on said curved levers, substantially as described.

3. The combination, with the curved levers partially surrounding the axle, and the weighted governor-arms thereon, of the pivoted 100 gravity stop or latch and the rods or links directly connecting said levers and latch, substantially as described.

4. The weighted axle-levers or governor-arms made each in a single piece in elbow or 105 bell-crank form, and provided with the concave end for engaging the curved pendent levers, substantially as described.

5. The combination, in an automatic brake mechanism, of the weighted axle-levers or 110 governor-arms, the pendent curved levers embracing the axle, the pendent pivoted latch-lever connected to said curved levers, and the cam-lever for setting or releasing the pivoted dog on the sliding draw-bar, substantially 115 as described.

6. The combination, with the sliding draw-bar, of the pendent bracket or hanger a, the pivoted dog D, the brake-lever E, cam-lever F, and spring l for holding the cam-lever normally in position to be engaged by the gravity stop or latch, substantially as described.

7. The cam-lever F, provided with the curved heel-extension f, in combination with the spring l, arranged and operating substantially as described.

In testimony whereof I have hereunto set my hand this 31st day of January, A. D. 1885.

STILLMAN W. ROBINSON.
